UNITED STATES PATENT OFFICE.

WILLIAM ALSOP, OF NEWCASTLE, NEAR SYDNEY, NEW SOUTH WALES,
AUSTRALIA.

ROTARY ENGINE.

SPECIFICATION forming part of Letters Patent No. 706,372, dated August 5, 1902.

Application filed June 17, 1901. Serial No. 64,940. (No model.)

To all whom it may concern:

Be it known that I, WILLIAM ALSOP, engineer, a subject of the King of Great Britain, residing at Newcastle, near Sydney, in the 5 State of New South Wales and Commonwealth of Australia, have invented new and useful Improvements in Rotary Engines, of which the following is a specification.

Rotary engines constructed according to 10 this invention are of the simple or compound type for steam, gas, air, and other expansive fluid pressure. In these rotary engines a casing, preferably cylindrical, incloses one or more disks or hubs attached to a shaft free 15 to revolve in suitable bearings. The disks are not rigidly fixed to the shaft, but are allowed sufficient movement about the shaft to attain their own center of gyration when running at high speeds, and so secure perfect balance without slip in the direction or at any angle to the true plane of rotation. On the disk or disks are a number of double curved vanes parallel to the axis of rotation and having a cross-section approximating to that of 20 a cone with curved sides, of which the axis is radial to the center of the disk. Both sides of the vanes have similar curved surfaces, and they are also perforated with a number of holes from side to side. At suitable positions in the casing are one or more orifices 25 through which steam, &c., at the initial pressure is directed to impinge on one of the curved surfaces of each vane as the disk rotates. As the velocity of the entering steam 30 or gas is always much greater than that of the vanes, a certain portion of it will pass through the holes in the vane nearest to the jet and impinge on the next vane, the perforations in alternate vanes being spaced so that the 35 perforations in one vane are opposite the spaces between the perforations in the next vane. These perforations prevent the steam rebounding from the vanes and reacting on the jet or on the vane next following that on 40 which the jet is acting direct. After the steam or gas from the initial directing-orifice has acted on the vanes through the arc of a circle it passes tangentially from them through an opening in the casing into a receiver opening to the atmosphere or to a con-

denser. In compound engines there are one or more steam-receivers with curved sides, the first of which guides the used steam to another directing-orifice, so that it will again impinge on the vanes and act on them through 55 the arc of a circle, from which it either exhausts into the atmosphere, or into a condenser, or into a second receiver, and then through another orifice again onto the vanes. The casing is built with receivers and orifices 60 in number proportionate to the initial pressure of the steam or gas used, so as to allow of its complete expansion down to the pressure of the atmosphere or that of the condenser. When the engine is required to be 65 a reversible one, one or more additional initial oppositely-directing orifices are placed in the casing with one or more exhaust-passages, receivers, and intermediate or low-pressure directing-orifices. The starting, stopping, or 70 reversing of the engine is controlled by one valve. For starting the engine under a load the starting-valve is moved to a certain position, allowing high-pressure steam to pass through the intermediate and low-pressure 75 directing-orifices, whichever way the engine is required to run, and then after the start the valve is returned, may be automatically, to its controlling position. When it is necessary for the engine to run at a constant speed, 80 the supply of the steam is controlled by a governor, which acts on a throttle-valve, or preferably on an arrangement for reducing the area of the initial directing-orifices. Any desired speed-reducing gear can be applied to 85 this engine, as required; but in order that this invention may be clearly understood reference will now be made to the drawings here- with, in which—

Figure 1 is an elevation of a compound reversible steam, &c., engine constructed according to this invention, while Fig. 2 is a vertical section of the same on line 2 2 of Fig. 1. Fig. 3 is a vertical section on line 3 3 of Fig. 4, while Fig. 4 is a similar section on the 95 line 4 4 of Fig. 3, respectively, of a triple-impulse reversible engine constructed according to this invention. Fig. 5 is a similar view to Fig. 4 of a quadruple-impulse non-reversible engine constructed according to this 100

invention. Fig. 6 is a plan of the starting slide-valve, showing in dotted lines the engine-ports as used for the engine illustrated in Figs. 1 and 2. Fig. 7 is a similar view of 5 the starting slide-valve used in the engine shown in Figs. 3 and 4, and Fig. 8 is a view of the starting slide-valve as used in the engine shown in Fig. 5.

The casing A is turned or shaped out, and 10 it has a solid back A' and a cover A² fixed to it by studs and nuts A³. It has a flat face A⁴, preferably at the top, having flanges A⁵, to which are bolted and studded the port-faces B and the cover B', through which is the sup- 15 ply-port B², to which an ordinary steam or fluid pressure supply pipe is fixed by flanges and bolts B³ or otherwise. Within this casing are various ports for the supply and exhaust of the steam. The initial sup- 20 ply-ports are marked C. The first directing-orifice on the go-ahead side is marked D. A port or passage E leads the somewhat-spent steam to the second directing-orifice F, while G is the exhaust-receiver, and G' a pipe to 25 waste or condenser. The first directing-orifice on the reverse or go-aft side is marked H. The port or passage J leads the somewhat-spent steam to the second directing-orifice K.

30 The main shaft L has at either side bearings L', and it passes through glands or dust-boxes L² at either side of the casing A. This shaft L carries or supports the disk M by reason of the squared boss L³ passing through and 35 fitting one size of an oblong orifice, in which is india-rubber or other resilient packing L⁴ at two opposite ends. This oblong orifice is through a box L⁵, which in turn passes through and fits one size of another oblong 40 orifice, while the other ends have similar resilient packing L⁶ opposite relatively to the ends of the inner oblong orifice which contains the packing L⁴. The boss L³ and the oblong box L⁵, together with the resilient 45 packings L⁴ and L⁶, are all kept in place by the disks L⁷ and M⁷, fastened to the disk M. By this means as the disk is revolved there is sufficient rigidity to keep it stiffly upon the shaft, while at the same time sufficient resiliency is allowed to obtain a perfectly-balanced 50 position and to revolve the shaft with ease. The disk M has flanges M', between which are the vanes N, as shown, these vanes having perforations N' also, as shown, in such a 55 way that the perforations of two contiguous vanes are not in juxtaposition.

With the main parts as before described there are of course auxiliaries which are novel in their combinations. There are starting, 60 stopping, and reversing mechanisms, there are valves for connection with governing mechanisms for regulating the speed of the engines, there are ports or passages within the casing for the conveyance of the steam 65 and partly-spent steam, and there are regulating-gates on these ports or passages for

contracting or enlarging the directing-orifices.

At the end of the ports or passages in the casing which lead from one part of the cylinder to another to convey the partially-spent steam in order that it may be utilized again there are regulating-gates f. These consist of resilient material screwed at one end f' to the interior facing of the port or passage and having at the other end one or more set-screws f², adapted to push or press the resilient material into the passage or orifice, and so contract it, and adapted on their unscrewing to allow the resilient material to recover 80 the normal position and enlarge such passage or orifice.

At the initial directing-orifices D and H are valves c, adapted to take on and partially close the entrance. These valves are on spindle c' and are actuated by radius-bars c², jointed by connecting-rods c³ to a cross-head c⁴ on spindle c⁵, which is connected up in any approved manner with a governor or other speed-regulating device, so that on the speed 90 of the engine exceeding the desired point the valves c will be moved toward the orifices D and H and reduce their area and consequently the amount of steam flowing therethrough and also the amount of steam impinging 95 against the vanes of the driving-disks.

Referring to Figs. 1, 2, and 6, O is a slide-valve with ports O' on a rod O², passing through stuffing-box O³ and knuckle-jointed at O⁴ to starting-handle P, jointed to bracket P' from the casing. This hand-lever works on sector P² and has spring-notch to gear therewith in the "go-ahead," "stop," and "go-aft" positions, as well understood. This lever P is extended beyond its joint-pin 105 by radius-bar P³, to which is connected the rod Q, jointed to lever Q' on fulcrum-pin Q², and the other end of which actuates sliding bar or rod Q³, connected to radius-rods Q⁴ on the spindle of throttle-valves Q⁵. In 110 operation steam, &c., is turned into orifice B² and the handle P thrown over, so that one of the ports O' is in juxtaposition with port C. Steam thereupon finds its way through 115 one or other of the orifices D or H, as shown in the drawings through orifice D, impinging against the vanes N of the disk M. The impact starts the disk M, and thereby revolves the shaft L. As the steam collects in passage E it again forms a jet which is directed 120 through orifice F, impinging again on the vanes and assisting in the revolution of the disk and shaft. Reaching the chamber G it passes through the open passage G' through to the atmosphere or to a condenser. To 125 reverse the engine, the handle P is thrown over to the opposite notch in the sector P², and the port O' is thus placed in juxtaposition with the port C, causing the jet to find its way in through orifice H and impinge on 130 the other sides of the vanes. The partially-spent steam collects in chamber J and forms

another jet onto the vanes in orifice K, and thence finds its way to receiver G and through the passage-pipe G' to the atmosphere or a condenser. It will be seen that as the valve 5 is reversed so are the throttle-valves Q⁵.

- Referring to Figs. 3, 4, and 7, the steam in the go-ahead position of the gear after passing through passages E and J and orifices F and K, respectively, collects itself in passages 10 R and T and forms a third jet through orifices S and U, respectively, so enabling triple impulse to be effected by the one supply of steam. In addition to the passages described with reference to the Figs. 1, 2, and 6 auxiliary ports C' are provided, having offsets C² 15 into passages E and J and offsets C³ into passages R and T in order that live steam at the initial pressure may be used to give the first movement to the disks, as might be required 20 where the engine carries a heavy load. The steam, &c., is supplied to these ports C' through additional ports O⁵ in the valve, which ports, as shown in the drawings, may be placed in juxtaposition with the ports C'. 25 In this case the handle P is adapted to be thrown over farther than is required in the normal acting or operating position, and it is thrown over by the attendant against the action of a spring P^X, whose resiliency recovers 30 the handle to its notch and the valve to the normal operating position. The operation of this engine is identical with that previously described, except in so far as the initial impulse of live steam obtained by the auxiliary 35 ports or passages and the throwing over of the lever for such purposes and in having triple impulse instead of but one impulse.

Referring to Figs. 5 and 8, the ports are principally the same as those described in the 40 previous paragraphs, with the exception that there are no reverse ports, although there are the auxiliary initial impulse-ports and further or quadruple impulse-passage V with directing-orifices W, and that from the exhaust-45 receiver there is one exit-pipe Y.

Having now particularly described and ascertained the nature of my said invention and in what manner the same is to be performed, I declare that what I claim is—

50 1. In rotary engines of the class set forth the combination with a driving-disk in a casing, of duplicate initial directing-orifices and duplicate sets of ports and passages with further directing-orifices and with controlling devices 55 so that the direction of travel of the disk may be reversed, substantially as herein described and explained.

2. In rotary engines of the class set forth, the combination with the steam-ports directing-orifices and controlling devices, of additional or auxiliary ports or passages from the initial steam-supply to one or more of further directing-orifices for starting the disk to revolve, substantially as herein described and 65 explained.

3. In a rotary engine, the combination with

a driving-disk, of a series of vanes arranged in suitable relation thereto and each provided with an opening, the opening of each alternate vane arranged out of alinement with the 70 opening of the adjacent vane.

4. In a rotary engine, the combination with a driving-disk, of a series of radially-extending vanes formed integral with the disk and each provided with a transversely-extending opening, the opening of one vane being out of alinement with the opening of the adjacent vane. 75

5. In a rotary engine of the class set forth, a main shaft, bearings therefor, a disk for driving said shaft, resilient packing mounted in oblong orifices for connecting the shaft to the disk, and a series of vanes arranged in suitable relation to said disk and each provided with an opening, the opening of each alternate vane arranged out of alinement with the 80 opening of the adjacent vane.

6. In a rotary engine of the class set forth, a main shaft provided with a squared boss, a driving-disk having an oblong orifice, a box 90 mounted therein, resilient packing interposed between said box and said shaft, resilient packing interposed between said box and disk, a series of vanes carried by the disk, each provided with a transversely-extending 95 opening, and means for directing a motive fluid to act on and exhaust from said vanes directly and tangentially in the plane of their rotation.

7. In a rotary engine of the class set forth, 100 the combination with a casing and a driving-disk mounted therein, of an initial directing-orifice for the motive fluid to impact with the disk, for imparting movement thereto, a redirecting-orifice for collecting the spent motive fluid to use the same for further impacting with the disk, a passage for establishing communication between the said redirecting-orifice and the disk, and means for regulating the passage of the motive fluid from the redirecting-orifice to the disk. 105

8. In a rotary engine of the class set forth, the combination with a casing and driving-disk mounted therein, of a series of vanes formed integral with the disk and each provided with a transversely-extending opening, the opening of one vane being out of alinement with the opening of the adjacent vane, an initial directing-orifice for the motive fluid to impact with the said vanes for imparting 120 motion thereto, and means arranged in said casing for collecting the spent motive fluid after its impact with the vanes and then further directing said spent motive fluid against said vanes for causing an additional impulse 125 thereof.

9. In a rotary engine, a drive-disk provided with perforated vanes suitably extending therefrom, the perforation of each alternate vane being out of alinement with the perforation of the adjacent vane, means for initially directing the motive fluid to impact 130

with the said vanes for imparting movement to the disk, and means for collecting the spent motive fluid after its impact with the vanes and for further directing said spent motive fluid against the vanes for causing an additional impulse to the disk.

10. In a rotary engine, a drive-disk provided with perforated vanes suitably extending therefrom, means for initially directing the motive fluid to impact with the said vanes for imparting movement to the disk, means for collecting the spent motive fluid after its impact with the vanes and for further directing said spent motive fluid against the vanes for causing an additional impulse to the disk, means for regulating the passage of the motive fluid from said collecting means to the vanes, and means for reversing the movement of said disk.
15. 11. In a rotary engine of the class set forth, the combination with a casing and driving-disk mounted therein, of an initial directing-orifice for the motive fluid to impact with the said disk for imparting motion thereto, means arranged in said casing for collecting the spent motive fluid after its impact with the disk and for further directing said spent motive fluid against said disk for causing an additional impulse thereof, means for regulating the passage of the motive fluid from said collecting means to the disk, and means for reversing the movement of said disk.
20. 12. In a rotary engine of the class set forth, the combination with a casing and driving-disk mounted therein, of an initial directing-orifice for the motive fluid to impact with the said disk for imparting motion thereto, means arranged in said casing for collecting the spent motive fluid after its impact with the disk and for further directing said spent motive fluid against said disk for causing an additional impulse thereof, means for regulating the passage of the motive fluid from said collecting means to the disk, and means for reversing the movement of said disk.
25. 13. In a rotary engine of the class set forth, the combination with a casing and a drive-disk mounted therein, of means for initially directing the motive fluid to impact with the said disk for imparting movement thereto, means arranged in said casing for collecting the spent motive fluid after its impact with the disk and for further directing said spent motive fluid against said disk for causing an additional impulse thereto, means for regulating the passage of the motive fluid from said collecting means to the disk, means for reversing the movement of said disk, and a valve mechanism for exhausting the motive fluid.
30. 14. In a rotary engine of the class set forth, the combination with a casing and a drive-disk mounted therein, of means for initially directing the motive fluid to impact with the said disk for imparting movement thereto, means arranged in said casing for collecting the spent motive fluid after its impact with the disk and for further directing said spent motive fluid against said disk for causing an additional impulse thereto, means for regulating the passage of the motive fluid from said collecting means to the disk, a valve mechanism for exhausting the motive fluid from said casing, and means for reversing the movement of said disk, causing thereby the simultaneous reversing of the exhausting valve mechanism.
35. 15. In a rotary engine of the class set forth, a drive-disk mounted in a suitable casing,

means for supplying motive fluid to said disk for operating the same, means arranged in the casing for collecting the spent motive fluid after its impact with the disk and for further directing said spent motive fluid against the disk for causing an additional impulse thereof, means for regulating the passage of the motive fluid from said collecting means to the disk a valve mechanism for exhausting the motive fluid from said casing, and means for reversing the supply of motive fluid to the disk causing a different movement to be imparted thereto and for simultaneously reversing the exhaust valve mechanism.

16. In a rotary engine, the combination with the casing and a driving-disk arranged therein, of means to permit of a motive fluid impacting with the disk for operating the same, means arranged in said casing for collecting the spent motive fluid, a passage for establishing communication between said collecting means and the disk, and means arranged in said passage for regulating the flow of the spent motive fluid from the collecting means to the disk and to permit of the spent motive fluid impacting with the disk for imparting additional impulses to the disk.

17. In a rotary engine, the combination with the casing and a disk arranged therein, of means for operating the same, means arranged in said casing for collecting and causing the spent motive fluid to impact with the disk for giving additional impulses thereto, means for regulating the impact of the said spent motive fluid, a valve mechanism for exhausting the motive fluid from the casing, and means for reversing the movement of the disk and for simultaneously reversing the exhaust valve mechanism.

18. In a rotary engine, the combination with a driving-disk, of a series of vanes arranged in suitable relation thereto and each provided with an opening, the opening of each alternate vane arranged out of alignment with the opening of the adjacent vane, and means for directing a motive fluid to act on and exhaust from the said vanes directly and tangentially in the plane of their rotation.

19. In a rotary engine, the combination with a driving-disk, of a series of radially-extend-

ing vanes formed integral with the disk and each provided with a transversely-extending opening, the opening of one vane being out of alignment with the opening of the adjacent vane, and means for directing a motive fluid to act on and exhaust from the vanes directly and tangentially in the plane of their rotation.

In testimony whereof I have signed my name to this specification in the presence of 10 two subscribing witnesses.

WILLIAM ALSOP.
